UNITED STATES PATENT OFFICE.

GIULIO MARCHETTI, OF HALIFAX, COUNTY OF YORK, ENGLAND.

DESIGN FOR A RUG.

SPECIFICATION forming part of Design No. 18,680, dated October 9, 1888.

Application filed September 13, 1888. Serial No. 285,318. Term of patent 3½ years.

To all whom it may concern:

Be it known that I, GIULIO MARCHETTI, of Halifax, England, have invented a certain new and original Design for Rugs; and I do hereby 5 declare the following to be a full, clear, and exact description of same, such as will enable others skilled in the art to which it appertains to make and use the design, reference being had to the accompanying photograph, which forms 10 a part of this specification.

My invention relates to a design for rugs; and it consists in a novel ornamentation of a filling or body of the rug and the border surrounding the same, substantially as hereinafter 15 described, and pointed out in the claim.

The accompanying photograph is a plan view of a rug embodying my design.

A represents the filling or body design of the rug, consisting of an all-over or equally- 20 distributed effect composed of small Indian branches, leaves, and blossoms conventionally 25

treated. B are two panels forming the head of the rug. The design in said panels is of fine all-over Indian tracery representing branches and blossoms conventionally treated 25 and ornamented. The figure C at the base of the rug, surrounded by smaller Indian work, is also of Indian character and ornamental in style.

D E F are the inner and outer borders surrounding the filling or body design of the rug. The borders are of fine tracery, representing conventional branches, leaves, and blossoms. The whole, being Indian in character, harmonizes completely with the body filling A. 30 35

I claim—

The design for rugs represented in the accompanying photograph.

GIULIO MARCHETTI.
